DRILLING MACHINE

John W. Peacock, Paola, Kans., assignor to The Peacock Special Machine & Drilling Company, Paola, Kans., a corporation of Delaware

Application June 26, 1934, Serial No. 732,520

4 Claims. (Cl. 255—2)

The invention relates to a drilling machine and more especially to portable or motor driven drilling rigs.

The primary object of the invention is the provision of a machine of this character, wherein a slide frame supports a motor, preferably of the internal combustion type, so that the machine is self-propelled and the operating parts are actuated by such motor, the parts being controlled through the transmission so that the same can be reversed without requiring the reversing of the motor, and one operated independently of the other.

Another object of the invention is the provision of a machine of this character, wherein the drilling tool is susceptible of a quick dropping stroke and both the lift and dropping strokes for said tool being controlled in a novel manner, while in association with the drilling tool is a shock absorber relieving it from shocks and jars, which is resultant in maximum life to the machine and assures snap and a lengthened stroke thereto.

A further object of the invention is the provision of a machine of this character, wherein a series of tools are susceptible of operation and control and these being capable of performing their functions independently of each other without interference of one by the other, with the result that a drilling job can be completed with rapidity and without excessive labor, the operation of the tool being carried forth by a single power motor.

A still further object of the invention is the provision of a machine of this character which is comparatively simple in its construction, thoroughly reliable and efficient in its operations, positive of action, conveniently controlled, susceptible of performing varying tool jobs in the drilling of wells, strong, durable, and inexpensive to manufacture.

With these and other objects in view, the invention consists in the features of construction, combination and arrangement of parts as will be hereinafter more fully described in detail, illustrated in the accompanying drawings which disclose the preferred embodiment of the invention, and pointed out in the claims hereunto appended.

In the accompanying drawings:

Figure 1 is a side elevation of the drilling machine constructed in accordance with the invention and adjusted or positioned for well drilling purposes.

Figure 2 is a top plan view thereof.

Figure 3 is a view similar to Figure 1 looking toward the opposite side of the machine, the same

being reversed as to position and the derrick being shifted to an inactive position so that the machine may travel from one locality to another.

Figure 4 is a vertical longitudinal sectional view through the derrick.

Figure 5 is a fragmentary elevation showing the gage attachment.

Figure 6 is a plan view of said gage attachment.

Figure 7 is a fragmentary side elevation of the stroke beam showing by full lines the range of 10 the tool lift and by dotted lines the range of the tool fall.

Figure 8 is a fragmentary side elevation, partly in section, of the shift bearings for the driven connections of certain of the cable drums.

Figure 9 is a plan view thereof.

Figure 10 is a detail sectional view of one power transmission.

Figure 11 is a sectional view on the line 11—11 of Figure 10 looking in the direction of the arrows.

Figure 12 is an enlarged sectional view on the line 12—12 of Figure 1 looking in the direction of the arrows.

Figure 13 is a fragmentary sectional view on the line 13—13 of Figure 1 looking in the direction 25 of the arrows.

Figure 14 is a fragmentary sectional view on the line 14—14 of Figure 1 looking in the direction of the arrows.

Figure 15 is a sectional view on the line 15—15 of Figure 1 looking in the direction of the arrows.

Figure 16 is a fragmentary transverse sectional view on the line 16—16 of Figure 1.

Figure 17 is a fragmentary sectional view on the line 17—17 of Figure 1 looking in the direction of the arrows.

Figure 18 is a fragmentary detail elevation of the combined clutch and brake mechanism for a drum control of the machine.

Figure 19 is a plan view thereof.

Similar reference characters indicate corresponding parts throughout the several views in the drawings.

Referring to the drawings in detail, the drilling machine or rig comprises a body frame, designated generally at A, and at its forward end are front steering wheels 10, while at the rear end of this frame is a crawling traction mechanism 11 having the usual endless tread belts 12, so that the machine can be propelled for travel upon 50 soft ground or snow, and positive traction is assured.

Within the frame A is a power motor 13, in this instance, of the internal combustion type, and its driving shaft 14, through the connecting belts 55

15 and 16, respectively, transmits power to the traction mechanism 11 for the driving of its belts 12. The power shaft 14 of the motor carries the sprocket wheel 17 for the belt 15 and the traction mechanism 11 has its driven shaft 18 carrying the belt wheels 19 for the belt 16, it being understood that these pulleys are located at opposite sides of the frame. The belt 15 is also trained over a sprocket wheel 20 fixed to a driven shaft 21 journaled in bearings 22 transversely of the frame A, the bearings being fixed in the latter in any suitable manner, while each belt 16 is trained over a belt wheel 23 loose on the driven shaft 21 and made secure thereto by a clutch 24, there being two of these clutches for the pair of belt wheels 23 and such clutches 24 are independently operated through a shift lever 25 capable of manual control for the clutching action. The pair of belts 16 and the belt wheels 19 and 23 therefore are provided in conformity with the character of the traction mechanism 11, as this includes a traction belt 12 at each side of the frame A of the machine and the driving of these belts independently of each other can be had by providing the clutches 24.

At the forward or front end of the frame A is arranged a swinging derrick or crane B having the trussed rig 26 fitted in a saddle 27 which is pivoted at 28 to mountings 29 on the body frame A, so that said derrick B can be swung from an upstanding operating position, as in Figure 1, to a superimposed transporting position on the body frame A, as in Figure 3 of the drawings.

Arranged within the frame A is a bull wheel 30, its axle 31 being journaled in slideable bearing boxes 32, these fitting guide pieces or brackets 33 suitably built into the frame and said boxes have connected thereto shift rods 34 for their adjustment, the rods being manually controlled. The axle 31 for the bull wheel 30 is formed with a crank end 35 to which is connected a pitman 36 which is connected, at 37, to a spudding or stroke beam 38 pivoted for its swinging movement, at 39, in the frame A, the connection 37 for the pitman 36 being eccentric to the axis of the bull wheel 30 so that the lift stroke of the beam 38 will be considerably greater than the fall or drop stroke thereof, or, in other words, the crank end 35 will be required to travel approximately two-thirds of the circular course thereof for the completion of the lift stroke of the beam 38, while the fall or drop stroke requires the remaining approximate one-third of the circle for the completion thereof for a purpose presently described.

The power shaft 14 of the motor 13 carries the belt wheel 40, over which is trained a driven belt 41, the same being trained over a belt wheel 42 upon an auxiliary drive shaft 43 journaled in bearings 44 fitted in the frame A, this shaft being disposed transversely of said frame and carrying a belt pulley 45 having trained thereover the belt 46 which is also trained over the bull wheel 30 so that power from the motor 13 will be transmitted to the bull wheel.

In the frame A, at opposite sides with respect to the shaft 43, are arranged the upper and lower shafts 47 and 48, respectively, these shafts 48 being fixedly journaled in suitable bearings 49, built into the frame A, while each shaft 47 is supported in a swiveled bearing 50 and a slide bearing 51, respectively, so that this shaft can be swung in a horizontal plane. The shafts 47 have fixed thereto gears 51' adapted to be brought into and out of mesh with a pinion 52 loose upon the shaft 43 and this pinion is formed with a brake drum

53 and one member 54 of a clutch, the other member 55 of the latter being splined or keyed upon the shaft 43 and operated upon by a throw lever 56 operable from a control 57, so that the part 55 can be brought into engagement with or out of engagement from the part 54 of said clutch, and the control 57 being manually operated. Embracing the drum 53 is a brake band 58 which is tightened for braking purposes by a lever 59, the same being arranged in the path of movement of the throw lever 56 when the part 55 is thrown out of engagement with the part 54 of said clutch, so that on the release of the clutch the brake will be applied. When the clutch is engaged the brake will be released so that power from the auxiliary shaft 43 will be transmitted to the shaft 47, provided the gears 51 thereon are meshing with the pinion 52 controlled by the said clutch and brake.

Fitted upon each shaft 47 is a transmission and reverse mechanism including a circular housing 60 having journaled therein a train of transmission gears 61, 62, 63 and 64, respectively, the housing being open, at 65, for accommodating the gear 66 fixed to each of the shafts 48 so that the gears 63 and 64 can be brought alternately into mesh therewith. The gear 63 meshes with the gear 62 which meshes with the gear 61, while the gear 64 meshes with the said gear 61 and this gear is fixed to the shaft 47. The housing 60 is rotated clockwise and counterclockwise by a control 67, so that the gear transmission can be regulated for reversing the drive of the shaft 48 and the transmission of power thereto either clockwise or counterclockwise, the control 67 being manually operated.

Fixed upon one of the shafts 48 is a drill tool drum 68, while upon the other shaft 48 is fixed a utility drum 69, the drilling tool cable 70 being adapted to be wound on and unwound from the said drum 68, while the utility drum 69 is adapted for the winding thereon and the unwinding therefrom of a utility cable 71 and this drum may also carry a supplemental or additional utility cable 72.

Loose upon the shafts 47 are the drums 73 and 74, respectively, each at one end being provided with a brake drum 75 and a part 76 of a clutch, the part 77 of said clutch being keyed or splined with the shafts 47, while trained about the drum 50 is the brake band 78, this being controlled by the lever 79 in the path of the throw arm 80 for the part 77 of the clutch. On the throwing out of the clutch, the brake will be automatically and simultaneously applied. The drum 73 is adapted for the winding thereon and the unwinding therefrom of the measuring line or cable 81, while the drum 74 is adapted to have wound thereon and unwound therefrom the crane hook cable 82.

Within the frame A, on opposite sides of the shaft 21, are arranged the upper shafts 83 and 84, respectively, each mounted in a swiveled bearing 85 and a slide bearing 86, respectively. These shafts carry the gears 87 which are capable of being thrown into and out of mesh with the pinion 88 loose on the shaft 21. This pinion is formed with a brake drum 89 and the part 90 of a clutch, the part 91 of the latter being splined or keyed to said shaft 21 and moved by a throw lever 92, while surrounding the drum 91 is the brake band 93, this being operated by a lever 94 in the path of the lever 92 so that when the clutch is opened or thrown out the brake will be automatically and simultaneously applied therewith.

The shaft 83 has fixed thereto the bailing tool cable 95 which is adapted to be wound on and unwound therefrom, while the shaft 84 has loose thereon a crane cable drum 96, the same being 5 formed at one end with the brake drum 97 and the part 98 of a clutch, the other part 99 of the latter being splined or keyed upon said shaft 84 and operated by the throw lever 100 in the path of which is the brake band lever 101 controlling 10 the brake band 102 about the drum 97, the brake being released when the clutch is closed or its part 99 interfitted with the part 98 of said clutch. This drum 96 carries the crane cable 96'.

In the frame A, beneath the upper shaft 84, 15 is the lower shaft 103, this being journaled in fixed bearings 104 built into said frame and this shaft has fixed thereto a double drum 105 for the winding thereon and unwinding therefrom of the hook cables 106 and 107, respectively. The 20 shaft 103 also has fixed thereto a gear 108 cooperating with a transmission including the circular housing 109 containing the train of gears 110, these in number and arrangement being alike to the gears 61, 62, 63 and 64, respectively, 25 hereinbefore referred to, one gear of the train being fixed to the shaft 84 and the housing 109 is operated by a control 111, manually operable, so that the shaft 103 can be readily reversed for rotation clockwise or counterclockwise, while 30 power from the shaft 84 can be transferred to the shaft 103. It should be apparent that the transmissions hereinbefore referred to can be shifted to neutral so that power therethrough will be cut off to their cooperating parts. The 35 housings 60 and 109 are freely rotatable upon their supporting shafts and the same are moved by hand for the control of the transmissions.

Upon the spudding or stroke beam 38 are mounted suitable guide pulleys 112 for the drilling tool cable 70, while suitably arranged in the frame A are conventional pulleys 113 for the cables adapted to be wound on and unwound from the drums.

Located centrally of the derrick or crane B 45 and disposed longitudinally of the same is a guide tube or casement 114 in which is slidably fitted a mast 115 which, at its upper end, supports a pulley 116 arranged within a head 117 which is a part of the mast and is outside of the 50 derrick or crane. Over this pulley 116 is trained the drilling tool cable 70. The inner or lower end of the mast 115 carries a cross guide 118 fitted in guides 119 in the derrick or crane at the lower portion thereof beneath the cross piece 120 55 for the tube or casement 114, which cross piece is suitably secured in place within the derrick or crane. This cross guide 118 has fitted therewith the stems 121 of plungers 122, these operating against coiled springs 123 fitted within 60 barrels 124 suitably held within the lower portion of the derrick or crane and such springs 123 function as shock absorbers for the mast 115.

The derrick or crane B has supported thereon suitable guide pulleys 125 over which are trained 65 the other cables of the rig.

Carried by the derrick or crane B is a boom 126 which has its lower end connected with the saddle 27 through the medium of a universal joint or connector 127 and this boom carries 70 pulleys 128 for certain of the cables of the rig, one pulley carrying the cable 96' and the other the cable 82.

Mounted on the cross guide 118 is a pointer 129 co-operating with a graduated scale plate 130, the latter being carried by the derrick or 75

crane so that the pointer 129 will traverse the scale marks of said plate 130 and this will disclose the displacement of the mast 115 in the operation of the drilling machine.

Certain of the cables of the rig are provided 5 with hooks 131 at their free ends for hitching purposes in the drilling maneuver.

In the operation of the machine it will be apparent that the derrick or crane is swung from inactive position upon the frame A of the machine 10 to the working position as shown in Figure 1 of the drawings and the cables on the drums heretofore referred to can be let off of such drums as the occasion may require and said cables wound thereon under power from the 15 motor 13, the controls for the drums being selectively operated and the rotations of such drums reversed at the option of the operator of the machine.

The front steering wheels 10 are actuated by 20 steering mechanism 132 so that the machine, in transit, can be guided in the desired course.

The stroke action upon the drilling tool cable 25 70 is clearly shown in Figure 7 of the drawings and this stroke has a greater arc of movement than the fall or drop stroke for the tool, the cable 70 being let out from its drum 68 in conformity with the depth of cut of the well and, as heretofore stated, the drums in their working are independently controlled. The speed of the bull 30 35 wheel 30 is regulated by shifting the same for the tightening or slackening of the belt 46, the bull wheel 30 being shifted by the slide bearings 32 regulated by the controls 34.

The machine is advanced or moved in the desired course by the traction mechanism 11 having the traction belts 12 and these are operated independently or jointly through the clutches 24, the latter being manually thrown by operating the throw levers 25 hereinbefore described. 40

What is claimed is:

1. In a drilling machine a main frame, bearing boxes built into said frame and having longitudinal sliding movement therein, a bull wheel 45 having an axle journaled in said bearing box, a spudding beam swingingly mounted at one end on the frame, a crank operated by the bull wheel and carried by its axle, a pitman connected with the crank and to the spudding beam to have the lift stroke of the beam operate in an arc greater than the full stroke of said beam and a power source within the frame for driving said bull wheel.

2. In a drilling machine, a main frame, a drill tool drum, a shaft carrying said drum, bearings for said shaft, one being shiftable and the other fixed to permit swinging of said shaft, a driving gear journaled in said frame, a circular housing journaled on said shaft, a train of transmission gears journaled in said housing and arranged to allow certain of the train of said gears to alternately mesh with the driving gear and means connected with the housing for moving the same clockwise and counter-clockwise for the alternate engagement of said gears. 55

3. In a drilling machine, a main frame, a drill tool drum, a shaft carrying said drum, bearings for said shaft, one being shiftable and the other fixed to permit swinging of said shaft, a driving gear journaled in said frame, a circular housing journaled on said shaft, a train of transmission gears journaled in said housing and arranged to allow certain of the train of said gears to alternately mesh with the driving gear, means connected with the housing for moving the same 70 75

- clockwise and counter-clockwise for the alternate engagement of said gears and means associated with the drum and the shaft and operated to render the drum loose or fast on the shaft.
5. 4. In a drilling machine, a main frame, a drill tool drum, a shaft carrying said drum, bearings for said shaft, one being shiftable and the other fixed to permit swinging of said shaft, a driving gear journaled in said frame, a circular housing journaled on said shaft, a train of transmission gears journaled in said housing and arranged to allow certain of the train of said gears

to alternately mesh with the driving gear, means connected with the housing for moving the same clockwise and counter-clockwise for the alternate engagement of said gears, means associated with the drum and the shaft and operated to render the drum loose or fast on the shaft and brake mechanism cooperating with the drum and the last-named means for braking action upon the drum when the same becomes loose on the shaft.
